DESIGN FOR AN ATOMIZER

Kenneth K. Miller, Kalamazoo, Mich.

Application October 4, 1946, Serial No. 133,762

Term of patent 7 years

(Cl. D83—1)

To all whom it may concern:

Be it known that I, Kenneth K. Miller, a citizen of the United States, residing in Kalamazoo, county of Kalamazoo, State of Michigan, have invented a new, original, and ornamental Design for an Atomizer, of which the following is a specification, references being had to the accompanying drawing, forming a part thereof.

The figure is a view of one side of an atomizer, embodying my new design. The other side, not shown, is substantially like the side shown.

The dominant features of my design reside in the portion of the drawing shown in solid lines.

I claim:

The ornamental design for an atomizer, substantially as shown and described.

KENNETH K. MILLER.
